UNITED STATES PATENT OFFICE.

FRANK B. MALLORY, OF FLEMINGTON, NEW JERSEY.

SHUTTER-WORKER.

SPECIFICATION forming part of Letters Patent No. 373,147, dated November 15, 1887.

Application filed June 21, 1887. Serial No. 241,969. (No model.)

To all whom it may concern:

Be it known that I, FRANK B. MALLORY, a citizen of the United States, residing at Flemington, in the county of Hunterdon and State of New Jersey, have invented certain new and useful Improvements in Shutter-Workers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to shutter-workers; and it consists in certain constructions, combinations, and arrangements of parts, as will be hereinafter described, and pointed out in the claims, whereby an improved device for 20 working shutters is produced.

In the accompanying drawings, Figure 1 is a view, partly in section and partly in elevation, of my improved shutter-worker as applied to a window-frame and shutter. Fig. 2 25 is a perspective view of the shutter-worker. Fig. 3 is a view, partly in plan and partly in section, of a modified construction of the shutter-worker as applied to a window-frame and shutter. Fig. 4 is another modified construction 30 of the shutter-worker shown in perspective. Fig. 5 is a perspective view of still another modified construction of my shutter-worker. Fig. 6 is a vertical central section through the worm-wheel and center pin of my 35 shutter-worker. Fig. 7 is a similar section, the worm-wheel and worm being omitted. Figs. 8 and 9 are sectional views of the housing, showing modified constructions of the center or axial pin of the worm-wheel; and Fig. 40 10 is a section of the housing in front of the hinge-plate, forming part thereof.

Letters A, B in the drawings represent a pair of hinge-plates; C, a housing; D, a worm-wheel; E, a worm or screw; F, a shutter, and 45 G a window-frame.

The hinge-plate A is provided with a horizontal housing, C, having two horizontal walls, c c', and a vertical connecting-wall, c², which serves to strengthen the walls c c' and close 50 the housing on one side. The remaining por-

tions of the walls c c' are not connected, so that the worm-wheel D can be horizontally slipped between and fastened by a pivot or axial pin, d. The pivot-pin d is provided with a head, d', ornamental or plain, and may 55 have a small transverse pin, d², as seen in Fig. 6, in order to hold it in place; or a screw-thread, d³, may be provided, wherewith it is secured to the wall c, while a sharp point, d⁴, bites the wall c' below and thus steadies the 60 pin, as shown in Fig. 8. The pin d may also be riveted into the wall c', in which case it should not extend up to the wall c, in order to permit the worm-wheel to be slipped in place between it and the upper wall, c. The 65 worm-wheel is in every case a part of the hinge-plate, and its mounting upon the pin d between the walls c c' effects the union of the hinge-plates A, B, as seen. The circular portions of the walls c c' have a curved outer covering-plate, C', between them, which is hinged at c³ at or near the connecting-wall c', and closes the curved portion of the housing, thus protecting the worm-wheel D and screw E against dust, ice, and rain. This covering- 70 plate may be held closed by means of an ordinary spring, C², Fig. 4; or its elongated end portion, c⁴, may move in a staple, c⁵, as shown in dotted lines in Fig. 1, or other suitable known means for automatically closing it may 75 be employed.

In order to enable me to use the worm or screw on shank or shaft c⁶, (shown in Fig. 1 and described in my Patent No. 343,716, dated June 15, 1886,) I provide an elongated opening, e, having different diameters, as shown, in the wall formed by plate A, the hole being of a size sufficient to easily pass the screw through it into the housing. After being thus passed into the housing the worm or screw is 80 moved toward the connecting-wall c' into the smaller diameter of the opening e, and its shank c⁶ is inserted into a semi-cylindrical bearing, c⁷, formed on the said wall c', to which bearing it is secured by means of a vertical 85 lock-pin, e⁸, fastened to the housing by means of a head and nut, as shown in Figs. 6 and 7, or otherwise suitably secured. This pin e⁸ prevents the shank of the worm or screw from 90 leaving its semi-cylindrical bearing and crowd- 95 100

ing into the teeth of the screw-wheel D, and thus the shank of the screw or worm runs properly between the semi cylindrical bearings.

I have shown in Fig. 5 that a crown, worm, or screw wheel may be employed, instead of the ordinary worm-wheel, and in Fig. 3 I have shown a pair of parliament-hinges provided with my invention, in which construction the opening e is rendered unnecessary, inasmuch as the bearing of the screw-shank lies in the parting-line of the hinge-plates.

What I claim as my invention is—

1. The combination, with the hinge-plate A, provided with housing portions c c' c², one of which portions is formed with a half-bearing, c⁶, of the opening e and the axial pin d, worm-wheel D, pin e⁶, and worm or screw E, with its shank or shaft, substantially as and for the purpose described.
2. A shutter-worker housing comprising in its construction a hinged movable covering portion or plate, C', said plate swinging on its hinge-pin to admit of the introduction of the worm-wheel D between the horizontal walls of

the housing, and also accommodating itself to the movements of the shutter and automatically resuming its normal covering position, substantially as and for the purpose described.

3. In a shutter-worker, the combination of a hinge-plate, as A, provided with horizontal housing-walls c c' and vertical connecting-wall c², a hinged horizontally moving covering-plate, C', a hinge-plate, B, provided with a worm-wheel, D, and a worm, E, on a shaft or shank, e⁶, substantially as and for the purpose described.

4. The combination of the pin e⁶ with the housing portion c c' c², and worm E, and shaft e⁶, and worm-wheel D and its pin d of a shutter-worker, substantially as and for the purpose described.

In testimony whereof I affix my signature in presence of two witnesses.

FRANK B. MALLORY.
